CLAIM

The ornamental design for a brake component for a sliding unit track, as shown and described.

DESCRIPTION

FIG. 1 is a top front perspective view of a first embodiment of a brake component for a sliding unit track, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top front perspective view of a second embodiment of a brake component for a sliding unit track, showing my new design; and,

FIG. 9 is a top front perspective view of the first embodiment, shown in use.

The evenly spaced broken lines shown in the drawings depict portions of the article that form no part of the claimed design. The short-long-short dashed lines shown in FIG. 9 illustrate environmental structure that forms no part of the claimed design.
